UNITED STATES PATENT OFFICE.

THEODOR WALDEMAR TALLQVIST, OF HELSINGFORS, RUSSIA.

STETHOSCOPE.

No. 824,450.

Specification of Letters Patent.

Patented June 26, 1906.

Application filed October 7, 1905. Serial No. 281,813.

To all whom it may concern:

Be it known that I, THEODOR WALDEMAR TALLQVIST, doctor of medicin', a subject of the Emperor of Russia, residing in Helsingfors, in the Grand Duchy of Finland, Russia, have invented certain new and useful Improvements in Stethoscopes, of which the following is a specification.

The present invention comprises improvements in stethoscopes whereby the instrument can quickly be changed from the form it has in the pocket to the form it has when ready for use, the instrument being so constructed as to form a single piece without any loose parts, and, further, that the tube of the stethoscope may at the same time serve as a holder for a chemical thermometer. The usual instruments for examination which a doctor always carries with him are thus comprised in a single apparatus.

The invention is shown in the annexed drawings, wherein—

Figure 1 shows the stethoscope with folded disk in the shape it has when carried in the pocket. Fig. 2 shows a vertical section of the stethoscope. The thermometer is here shown in dotted lines. Fig. 3 shows the stethoscope ready for use. Fig. 4 is a horizontal projection of Fig. 3.

30 The disk, which as in other stethoscopes can be made of metal, wood, or other suitable material, is made either flat or concave on the side which lies against the ear of the doctor. The concave shape is the usual one and is shown in the drawings, Fig. 2.

As is seen from the annexed drawings, the disk is made in three parts, a center *a* and two side pieces *b*, which are hinged to the center piece. There are four hinges, of which two, *c*, are long and two, *d*, short to make it possible to turn the tube through ninety degrees. The center piece *a*, which like the side pieces *b* is flat on the side nearest the tube *f*, has a tubular flanged center *e*, which fits into a corresponding hollow in the tube *f*. The center piece *a* is fastened to the flanged tubular piece *e* by the flanges of the tube *g*, which is fixed and prevented from turning by the pin *h*. The center piece *a* and the side pieces *b*, fastened thereto by the hinges *c* and *d*, can, when the latter are opened out to lie in the same plane as the center piece *a*, be turned round on the end of the tube *f*, but not more than ninety degrees, 55 because the ends of the hinges *c* abut against the sides of the wider part *p* of the tube, Figs.

2 and 4. Through the stiffness of the hinges the side pieces *b* are held in the position shown in Fig. 1 when folded up.

When the stethoscope is to be used, the 60 side pieces *b* are folded out, as shown in Fig. 4, whereafter the tube *f* is turned round through an angle of ninety degrees. The lower enlargement *p* of the tube *f*, which lies against the disk, is flat and will lie across the 65 center piece *a* and the side pieces *b*, which cannot then be folded up. The stethoscope is now ready for use. The enlargement *p* of the tube *f* is provided with two grooves *k*, in which the hinges lie when the side pieces *b* 70 are folded up, and these hinges *c* prevent the turning of the tube *f* more than ninety degrees. The shorter hinges *d*, however, do not prevent the tube *f* from being turned round, Fig. 4. The tube *f* is provided with 75 a pin *l* when it is used as a holder for a fever-thermometer, the point of the thermometer resting against this pin. To hold the thermometer, there are two springs *m* and *n* in the upper part of the tube *f*, these springs being 80 connected by the rivet *p'* and partly closing the tube *f*. A single spring can, however, be used instead of the springs *m* and *n*. On pressing the pin *r* and turning the stethoscope so that the disk end is uppermost the 85 thermometer will slide out. The inner diameter of the tube *f* is made of such a size that the sound-waves have ample room to go through, and the stethoscope can therefore be used even if the thermometer is in it. The 90 thermometer is so fixed by the springs that it does not rattle or cause disturbing noises when the stethoscope is in use.

I declare that what I claim is—

1. In a stethoscope a tube, a center piece 95 secured to said tube two hinged pieces secured to said center piece and adapted to fold back over said tube, said center piece and hinged pieces forming the usual disk of the stethoscope means for locking said hinged pieces in their outward position.

2. In a stethoscope a tube, a center piece rotatably mounted on one end of said tube, two hinged pieces secured to said center piece and adapted to fold back over said tube, said center piece and hinged pieces forming the usual disk of the stethoscope, side projections on said tube abutting against said disk, means for permitting a partial rotation of said side projections relative to said disk. 105

3. In a stethoscope a tube means for removably holding a thermometer within said

tube, said means comprising a pin located across said tube and a hand-released spring device situated at one end of said tube, a folding disk secured to said tube and means for locking said folding disk in its open position.

4. In a stethoscope, a tube the usual disk at one end of said tube, a center part and two hinged pieces comprising said disk means for permitting rotation of said disk relative to said tube, and means in one position of said disk for holding said hinge-pieces flush with said center piece.

5. In a stethoscope a tube, the usual disk at one end of said tube, hinged pieces comprised in said disk, means for turning said hinged pieces back upon said tube, means for rotating said disk relative to said tube, projections on said tube, one hinge on each of

said hinged pieces out of the path of said projections and one hinge on each of said hinged pieces in the path of said projections for the purpose described.

6. In a stethoscope a tube, a second small tube inserted and held in said first tube, an annular flange on said second tube, a disk comprising a center and two side hinged pieces said center piece taking over and rotatable on said flange, projections on said tube, stops on said disk substantially as and for the purpose described.

In witness whereof I have hereunto signed my name, this 9th day of September, 1905, in the presence of two subscribing witnesses.

THEODOR WALDEMAR TALLQVIST.
